UNITED STATES PATENT OFFICE

2,508,694

MUSIC STAND

Russel L. Steed, Houston, Tex.

Application October 22, 1946, Serial No. 704,928

6 Claims. (Cl. 45—121)

1

This invention relates to music stands, designed to hold sheet music for use by musicians, the object thereof being to provide a stand which can be readily adjusted up and down for height to accommodate the particular musician, whether standing or sitting, and which can be readily taken apart and compactly folded to occupy a minimum of space when not in use, whereby when folded, it can be carried about by a musician in a bag, or in a small box or case approximately sixteen inches long and four inches in diameter, in addition to weighing only about three and one-half pounds.

Another object of the invention is to provide a music stand of simple and novel construction which can be very economically produced, and in which the parts may be readily assembled or folded as desired, for use, and for transportation, the device comprising a few simple parts capable of expeditious and economical manufacture.

Other objects and advantages reside in the details of construction and operation as more fully hereinafter described and claimed, reference being had to the accompanying drawings forming part hereof, wherein like numerals refer to like parts throughout, and in which:

Figure 1 is a front elevation of a music stand constructed in accordance with the invention;

Figure 2 is a side elevation thereof;

Figure 3 is a bottom view of the base member of the stand;

Figure 4 is a sectional view taken transversely to the plane of the head member which supports the music rack proper, parts being broken away;

Figure 5 is a vertical sectional view taken on the line 5—5 of Figure 4;

Figure 6 is a sectional elevation of a fragmentary portion of the base member and stand attached thereto;

Figure 7 is an inverted sectional elevation looking at the bottom of the structure shown in Figure 6, and

Figure 8 is a detail sectional view showing the manner of connecting the sections of the stand forming the upright or standard thereof.

Referring to the drawings in detail, in which like reference characters designate corresponding parts throughout the several views, the music stand is shown as comprising a base 10 upon which is supported an upright or standard 11 and upon the top of the latter, a music rack 12 designed to support the sheet music. The base 10 is designed to give steady support to the stand upon the floor, and comprises a frusto-conical heavy base member or casting 13 the lower por-

2

tion 14 of which is cylindrical and the top of which is provided with a reduced upright shank 15, which may be externally threaded and forms an annular shoulder or seat 16 therearound at the top of the casting 13. The bottom of the base member or casting 13 is hollowed-out as indicated at 17 and provided with three equidistantly spaced webs 18 forming a spider in the form of vertical partitions or walls therein terminating in a central hub or sleeve 19 having a downwardly opening threaded socket 20 at the bottom and center thereof. The walls or webs 18 are each provided with a transverse notch 21 at the bottom near the cylindrical wall 14 and all equidistantly spaced from the center or hub. In addition, the circular portion 14 is provided with notches 22 on each side of a web or wall 18 and thus two between each pair of webs, with notch or recess 22 diverging from said walls and from each other, the bases of the notches 21 and 22 being concaved or formed on concentric circles. The notches 21 take a ring 23 of circular cross-section, the ring being round and preferably formed of wire or the like. The ring 23 may be split or of integral formation, with the ends joined together or otherwise, to fit in the base member or casting 13 within the notches 21 in which it is snapped or frictionally held, in which event it may be a spring ring. Pivotally mounted on the ring 23 are a plurality of rebent or substantially U-shaped supporting feet or legs 24, the same having rounded or closed outer ends 25 and legs 26 forming the sides thereof, divergent outwardly and convergent inwardly, to pivotally mount the inner ends thereof or terminals 27 upon the ring 23 forming an annulus held in the notches 21, by means of transverse holes or notches 28 formed in said ends or terminals 27. In this manner, the feet or legs 24 can swing outwardly into the notches or grooves 22 on the annulus or ring 23 to outwardly inclined positions when spread apart to firmly support the stand on the floor. This is made possible by retaining means, consisting and providing a bottom circular recess 29 in the bottom face of the base member or casting 13 in which a circular plate or disc 30 is seated and provided if desired, with notches aligning with the notches or recesses 22 as indicated at 31, to receive the sides or legs 26 therethrough or permit the same to be folded inwardly in the same direction toward each other for compact folding. However, when the legs are extended in supporting position, they are retained by an outer plate or disc 32 smaller than the plate or disc

30 and having its peripheral bent at a slight angle downwardly as indicated at 33, to form a lip on which the legs rest and which press up against the legs, to permit the latter to extend downwardly and outwardly in an inclined or divergent position to support the stand at the closed ends or loops thereof which contact with the floor at 25. The plates are held in position by a screw shown as a wing screw 34 or other desired fastening means to render the same detachable. This screw is shown provided with a reduced threaded shank engaging the threaded socket 21 in the hub of the base member 13 and a slightly enlarged smooth cylindrical portion 35 outwardly thereof, to engage through corresponding openings in the discs or plates 30 and 32, thus detachably retaining the latter in position when the device is set up for use and permitting detachment thereof, for compactly folding the legs for storage or shipment. Obviously, the device can be compactly folded when not in use, so as to be carried around in a suitcase, bag or a special box or case for the purpose.

The upright or standard 11 comprises a tubular lower section 36 which fits over the shank 15 and may have an internally threaded socket slightly enlarged with respect to the bore of the tubular section 36, to thread over the threaded stem or shank 15 to detachably connect the same thereto, as shown in Figure 6 of the drawings. The standard or upright is of telescopic construction, and in addition to the lower tubular section 36, includes an intermediate tubular section 37, which may have similar threaded engagement within the tubular section 36 at its upper end, as indicated at 28. The upper end of the intermediate tubular section 37 receives therein an upper rod section 39, suitably connected thereto as by means of a set screw 40, the sections of the upright or standard being capable of disconnection or the upper rod section 39 may be telescoped into the intermediate tubular section 37.

The upper end of the upper circular rod section 39 is held in a coupling 41 which is provided with a socket 42 for this purpose, in which the upper end of the rod section 39 may be held by a wing screw 43 or the like. The upper end of the coupling 41 is provided with a diametrical slot 44 in which is pivotally mounted a circular plate or disc 45 at the axial center thereof as indicated at 46. A clamping wing or set screw 47 is threaded through the coupling 41 below the pivot 46, to frictionally engage the disc or plate 45 in order to hold the latter in angular relation to the coupling and thus the stand.

The upper edge of the plate or disc 45 is fixed in a slot 48 of a bifurcated lug or stem 49 forming a reduced portion extending axially or centrally down from a head member 50 formed as a casting or otherwise and of inverted frusto-conical formation with a cylindrical upper portion 51. The head piece or member 50 is formed with similar equi-distantly spaced radial and vertical webs or walls 52 forming a spider the same as the base member 13 and preferably three in number produced by cutouts or hollow portions 53 and forming a hub 54 at the center or axis vertically. The top edges of the walls 52 are provided with notches 55 transversely thereof and preferably circular, to receive a wire ring or the like 56 similar to the ring 23 but of larger diameter and smaller gauge wire. The rim or annular wall portion 51 is also provided with transverse radial notches 51 corresponding to the notches 22 and a series of arms 58 forming the music sheet rack 12 are provided

with apertures or notches extending transversely therethrough to receive the wire 56 which may be a solid or split ring as stated. Whereas three legs or feet 24 are shown at the bottom, eight or nine arms 58 may be employed at the top with a corresponding number of notches to receive the legs 59 thereof shaped the same as the legs of the feet 24 and forming the outwardly divergent and inwardly convergent sides thereof all sprung inwardly to engage the ring and notches. This produces additional friction at the engagement tending to hold the legs and arms in position. The sides 59 are adapted to be retained and lay in the notches 51 assisted by the weight of the arms, while the weight of the stand and rack hold the legs 24 outwardly, but are additionally retained in position by a cover plate or disc 60 secured over the flat top of the casting or head 50 removably, as by a central screw 61 engaging a threaded socket or bore in the hub 54. This cover plate 60 however is provided with radial notches or slots 62 at its peripheral edge, by which the arms 58 may be swung or sprung upwardly and inwardly toward each other, in order to collapse the rack 12 with the head, for compactly folding the same in order to conveniently carry the whole device about in a suitcase, bag or special box or case for the purpose, after separating the sections 36, 37 and 38 of the standard or upright 11 and folding the base 10 by removal of the bottom plate or retainer 32 after removing the screw 34 which clamps the legs 24 in supporting position. In order to support the sheet music upon the rack 12, a wire arched member extending perpendicular to one of the arms 58 may be provided as indicated at 63, comprising an inverted U-shaped wire section attached at its extremities to the sides 59 of one of the arms 58 which is disposed in a lower position. Obviously, the rack can be adjusted in any inclined position to support the sheet music thereon against the stop or loop 63, and the stand may be extended or collapsed for use in a standing or sitting position so that the music will be supported conveniently at the proper elevation to be turned as necessary. The device is composed of a few simple parts including wire, all parts being of metal or other suitable material and weighing about three and one-half pounds. When folded up, any musician can carry it in his bag or in a special case for the purpose. It can also be set up for use quickly and conveniently and forms a very practical stand for the purposes stated.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A music stand comprising a base member, an extensible standard detachably connected to said base member, a head member angularly adjustable on the upper end of the standard, said base and head members comprising circular body portions having peripheral notches extending radially, a retaining ring mounted therein, looped members having side portions pivoted to said ring and engageable in the notches in outwardly extending positions, said members being collapsible toward each other on the rings, and a page retaining member carried by one of said members on the head member.

2. A music stand comprising a base member,

an extensible standard detachably connected to said base member, a head member angularly adjustable on the upper end of the standard, said base and head members comprising circular body portions having peripheral notches extending radially, a retaining ring mounted therein, looped members having side portions pivoted to said ring and engageable in the notches in outwardly extending positions, said members being collapsible toward each other on the rings, a retaining plate secured to the base and head members over the first named members and an inverted U-shaped member carried by the side of one of said members on the head member, to support music sheets in an inclined position thereon.

3. A music stand comprising a base member, an extensible standard detachably connected to said base member, a head member angularly adjustable on the upper end of the standard, said base and head members comprising circular body portions having peripheral notches extending radially, a retaining ring mounted therein, looped members having side portions pivoted to said ring and engageable in the notches in outwardly extending positions, said members being collapsible toward each other on the rings, a retaining plate secured to the base and head members over the first named members and an inverted U-shaped member carried by the side of one of said members on the head member, to support music sheets in an inclined position thereon.

4. A music stand comprising a base including a casting having a hollowed-out portion forming radial webs with notches in the bottom edges thereof and forming a lateral wall with notches in the edges thereof, a ring seated in the notches of the webs, U-shaped legs having side portions pivoted on the ring and engaged in the notches and swingable on the ring toward each other to collapsed position, a retaining plate secured to the bottom of the base member and having notches receiving sides of the legs therein in inclined positions in supporting relation, a second plate over the first plate having an angularly bent portion retaining said legs in supporting position and removable to permit collapsing thereof, a sectional standard supported on the base including a lower tubular section detachably connected to the base at the center of the top thereof, a second section removably attached in the upper end of the lower section, a rod telescoping in the upper end of the second section and adapted to be clamped in a standard or collapsed position, a coupling removably mounted on the upper end of the upper section and having a slot therein, a plate mounted to turn in said slot, means to hold said plate in a different angularly adjustable position, a head member formed similarly to the base member in a reversed position and attached to the plate pivoted to the coupling, arms similar to said legs and a notched plate secured to the top of the head member and having notches through which said arms are adapted to swing upwardly toward each

other in collapsed position, and an inverted U-shaped member carried by one of the arms between the sides thereof to support music sheets thereon in inclined positions at the lower edges of the sheets.

5. A music stand comprising a base including a casting having a hollowed-out portion forming radial webs with notches in the bottom edges thereof and forming a lateral wall with notches in the edges thereof, a ring seated in the notches of the webs, U-shaped legs having side portions pivoted on the ring and engaged in the notches and swingable on the ring toward each other to collapsed position, a retaining plate secured to the bottom of the base member and having notches receiving sides of the legs therein in inclined positions in supporting relation, a second plate over the first plate having an angularly bent portion retaining said legs in supporting position and removable to permit collapsing thereof, a sectional standard supported on the base including a lower tubular section detachably connected to the base at the center of the top thereof, a second section removably attached in the upper end of the lower section, a rod telescoping in the upper end of the second section and adapted to be clamped in a standard or collapsed position, a coupling removably mounted on the upper end of the upper section and having a slot therein, a plate mounted to turn in said slot, means to hold said plate in a different angularly adjustable position, a head member formed similarly to the base member in a reversed position and attached to the plate pivoted to the coupling, arms similar to said legs and a notched plate secured to the top of the head member and having notches through which said arms are adapted to swing upwardly toward each other in collapsed position, a page retaining member on one of said arms to support music sheets on the arms in different angularly adjusted positions of the rack of the head member, said arms all being in the same plane to form a flat supporting surface.
6. The combination of claim 1 wherein, a spider web is secured in said circular body portions and said radial notches are located therein.
